UNITED STATES PATENT OFFICE.

OSCAR F. SMITH, OF NORRISTOWN, PENNSYLVANIA.

CLOTHES-DRIER.

SPECIFICATION forming part of Letters Patent No. 281,724, dated July 24, 1882.

Application filed February 5, 1883. (No model.)

To all whom it may concern:

Be it known that I, OSCAR F. SMITH, of the borough of Norristown, county of Montgomery, and State of Pennsylvania, have invented 5 certain new and useful Improvements in Clothes-Driers, of which this is a full, clear, and exact description, reference being had to the accompanying drawings, making part of this specification.

10 Figure 1 is a perspective view of a clothes-drier complete, (with three slats omitted,) in which the features of my invention are embraced. Fig. 2 is a top or plan view of the support-plate C, showing the mortises or openings 15 h, designed to hold the slats D erect when not in use. Fig. 3 is a side view of one of the slats D. Fig. 4 is a front view of the hanger-plate f, which is permanently cast or attached to the semicircular slat-holder B. Fig. 5 is a 20 sectional view through one of the slats D as arranged when in use.

My invention relates to the class of clothes-driers generally used within domestic apartments; and it consists, first, in the arrangement of a semicircular plate or slat-holder, B, having a downward-projecting hanger—on its chord—in which are tapering slots, to facilitate transfer and removal from the wall without the removal of attachment-screws. In the are 25 of the holder B are a number of radial slots, a, closed at their lower extremities, thus forming shoulders d, which support the slats D when inserted in said slots for use. In line with each of the slots an oblong opening, C, is made, 30 the intervening metal forming a cross-bar, e, which serves to support the slats D in a perpendicular position, this being effected by means of the slot n and lip o at the inner or lower end of the slat D, in connection with the mortise or 35 opening h, Fig. 2. The supporting-plate C is also semicircular. Its circle being less, it is readily placed within and under the holder B, and its special purpose is to steady and support any one or all of the slats D when folded up 40 out of use. It has three lugs, g, which rest upon the lugs m, Fig. 1, and it is thus held in position securely while the holder B is attached to the wall, but may be readily disconnected when the holder B is removed from the

wall. In its circle are openings h, corresponding in number with the radial slots contained in the holder B, said openings being slightly larger than the end of slats D. The latter are easily inserted when turned upright, and their insertion is facilitated by means of the beveled sides k and the upright flange l, forming its outer circle. When the slats are turned downward for use, they are supported by the fulcrum or shoulders d, and at the inner end the pressure is upward against the bottom of 50 the holder B.

My device possesses the important advantages of being folded upward out of the way where children cannot injure it, is readily transferred to different rooms, is cheaply 55 constructed of two light castings, B and C, requiring no machine-work, and the wooden slats D are easily made.

The holder-plate B, constructed as described, to wit, with radial slots a, oblong openings 70 c, shoulders d, cross-bars e, hanger-plate f, and lugs m—may be used without the supporting-plate C, by substituting for this supporting-plate a wire or upright thin flange located with in the semicircle of and underneath the slots a, 75 and supported by three or more arms projecting inward from the ledge or shoulders d, and located near the extremes and middle of the semicircle of the shoulder-rim, to be used in connection with the slats D, the slats D in 80 such case to have, in addition to slot n and lip o, a shallow recess or notch cut in its lower or inner end; or, in lieu of the supporting-plate C, the slats D may be grasped and supported, when folded, by a semicircular plate 85 having an equal number of elastic slots or recesses, said plate to be located near the upper end of the slats D when turned up out of the way. I prefer, however, to use the plate C in connection with the holder B, as first hereinabove 90 described, on account of the ease and facility of inserting the ends of the slats D, and as being more accurate in causing all of the slats D to stand erect parallel with each other. The use of the plate C also obviates the necessity of any machinery or parts being located 95 at an inconvenient height for supporting the upper end of the slats D when folded.

Having now described my invention, what I claim as new, and desire to secure by Letters Patent, is—

The holder-plate B, with its radial slots *a*, oblong openings *c*, shoulders *d*, cross-bars *e*, slotted hanger-plate *f* and lugs *m*, the plate C, with its lugs *g*, openings *h*, having beveled

sides *k*, and upright flange *l*, and the slats D, in combination, in the manner and for the purpose substantially as set forth.

OSCAR F. SMITH.
